MANUFACTURING COMPANY, A CORPORATION OF DELAWARE.

MECHANICALLY-ACTUATED DIAPHRAGM-HORN.

1,160,899.

Specification of Letters Patent. Patented Nov. 16, 1915.

Original application filed May 5, 1909, Serial No. 494,120. Divided and this application filed July 9, 1910.
Serial No. 571,188.

To all whom it may concern:

Be it known that I, MILLER REESE HUTCHISON, a citizen of the United States, and resident of New York city, in the county of New York and State of New York, have invented certain new and useful Improvements in Mechanically-Actuated Diaphragm-Horns, of which the following is a specification.

10 The improvements referred to are embodied in the automobile warning signal set forth in my prior application, Serial No. 494,120, filed May 5th, 1909, of which this application is a division.

15 They relate to cam operated diaphragm horns of the type set forth in my prior applications, Serial No. 305,933, filed March 14th, 1906 and Serial No. 373,946, filed May 16th, 1907, (granted May 25th, 1909, as 20 Patents Nos. 923,048, 923,049 and 923,122) which were co-pending with my said application of which this application is a division.

They consist of certain important features 25 of construction and operation whereby the basic principles set forth in said earlier application have been rendered practically useful and commercially successful.

In said earlier co-pending applications, I 30 disclosed certain devices and generic methods of producing sound by causing a thin steel diaphragm of suitable proportions, to execute bodily vibrations, bowing as a whole first on one side of its neutral or normal 35 plane and then on the other, by means of a rotary cam having cam projections of low pitch, spaced widely apart, and rotated at speed harmonizing with the natural times of the outward swing of the diaphragm.

40 The sound thus produced, consists mainly of a music like note consisting of the alternately rare and dense waves of air generated by the unitary vibration or bodily swing of the diaphragm as a whole. This 45 note is very easily distinguishable from the much more disagreeable, penetrating sound effect produced by concussion ripples of the diaphragm due to violent impacts when the latter are not timed so as to promote the 50 natural swing above referred to. My said co-pending applications disclosed fully how a device of this kind may be continuously operated to produce sound by this harmoni-

ous or bodily swing method but in the said applications, I nowhere contemplated or 55 provided for the practical difficulties in the way of using such devices for intermittent short signals which are most in use where the devices are used for my primary purpose of automobile warning signals. 60

For a commercially successful signal, it is not sufficient to harmonize the cam contacts to every second or third or fourth natural swing of the diaphragm. There must be a cam push for every natural swing. The 65 only way to get a substantial amplitude of the bodily movement at lower speeds, is to make the path of the cam projections greatly overlap the rest position of the diaphragm wearpiece so as to force a full outward movement of the diaphragm at every 70 cam contact. This heavy over-lap arrangement which is the one disclosed in my said Patents Nos. 923,048 and 923,122 gives the 75 desired note at the harmonized speeds but the power required at non-harmonizing speeds is many times that required at the higher harmonizing speeds. Hence it is necessary to have some means of applying great power initially and reducing the 80 power subsequently when full speed is attained as by operating the resistance, 35, shown in Patents Nos. 923,048 and 923,122, or equivalently relaxing the push on the foot pedal or the pull on the chain shown in 85 923,049. Consequently, while my said prior devices are theoretically and to some extent practically operable to produce a note by the harmonious body swing method, they are none of them adapted for the purposes 90 of a commercial automobile warning signal requiring brief, intermittent, instantaneously effective operation without special attention or skilled manipulation by the operator.

As a result of the above and other defects 95 in my prior devices, it was difficult to get diaphragms that would stand up a reasonable length of time during commercial operation. With commercial devices which I put upon the market in the form shown in 100 my Patent No. 923,049, whether with the heavy overlap described as preferred or with the light overlap described as capable of being utilized so as to give results, the operator, in the excitement caused by imminent danger, would press upon the foot 105

pedal or pull on the chain, with great violence so that the friction wheel would not slip sufficiently on the motor fly wheel. Thus the cam would be driven far above the 5 harmonized or synchronous speed, with the results that no diaphragm could withstand. The wearpiece would break loose from the diaphragm regardless of how secured, whether screwed, riveted, brazed or welded 10 and in case of operation at excessive speeds, the diaphragm became heated above the point where the temper of the steel was destroyed. With this understanding of the difficulties to be overcome my present invention will be 15 readily understood. It involves, among other things, devising a motor and energizing means, which are too feeble to permit the heavy overlap of cam and wearpiece; then adjusting the cam with such slight overlap 20 that no very powerful swing and reaction of the diaphragm will be built up until the full speed giving a cam push for every swing, has been reached. The motor should accelerate rapidly from a state of rest to the 25 desired full speed so that there is no opportunity for building up a wide diaphragm swing at any of the nonharmonious lower speeds. I prefer an electric motor having an armature of greater diameter than the 30 cam, so as to give powerful initial torque and the required rapid acceleration from rest to full speed. In this combination I prefer to use a cam of progressively increasing or accelerating pitch toward the tips so 35 that some concussion sound may be produced by the steep pitch engagement of the tips of the cams with the wearpiece during acceleration, when bodily movement of the dia- phragm is at minimum. Yet, when the full 40 speed of push for every swing has been reached, and the cam is engaging the dia- phragm in the rearward bowed position where it is nearly stationary, the engaging cam surfaces will be of much lower pitch. 45 The faces of the cam from this point of initial engagement onward to the tip are adapted to follow up the diaphragm and add increments to its outward movement throughout all the naturally accelerating 50 portion of the swing and beyond the normal or rest position where acceleration naturally ceases, it leaves the diaphragm substantially free to execute its natural outward movement and its rearward elastic return 55 behind the normal rest position.

In my present device, I still prefer to use the durable diaphragm materials and construction of the general type disclosed in my Patent 923,049 but by my present invention 60 where wide diaphragm swing is attained only at harmonious speed, the diaphragm materials and construction may be very inferior without rendering the device uncom- mercial.

65 Minor features and objects of my inven-

tion useful in the connections shown and in analogous relation will be evident from the detailed description of my invention.

From the above full description of the nature and objects of my invention, a concrete embodiment illustrated in the accompanying drawings will be readily understood from said drawings, in which—

Figure 1 is a vertical central section of the horn and motor assembled, the battery 75 connections being diagrammatically indicated; Fig. 2 is a central transverse section at right angles to the plane of Fig. 1; Figs. 3 and 4 are detail views of plane faced rotary cams; and Fig. 5 is a diagram illustrating rotary cam and diaphragm relations.

The general organization of the parts is shown in Figs. 1, and 2. The diaphragm 1 is clamped at the edges between two sections of an inclosing case. The rear section 2 is 85 formed with rear walls approximately parallel with the diaphragm, except where it is enlarged, as at 3 and 4, to form inclosing chambers for the cam, cam shaft, and bearings. The front face is formed with an annular clamping surface 5. The front cover or resonator section 6 of the diaphragm case is parallel with the diaphragm and far enough away from it to permit maximum vibration of the diaphragm without engagement with the case. It is formed with the central opening 7 of large diameter so as to expose a large part of the effectively vibrating part of the diaphragm. The opening is 90 surrounded by an annular flange 8, which may be flared toward the open end, as indicated at 9. The resonator 10 is secured to this flange preferably by spinning the material against the outer wall thereof or by 95 brazing or by both. The periphery of 6 is 100 formed with a flange 11 fitted over the rear section 2 of the diaphragm case. As shown in the drawings, the clamping surfaces are of ample width and thickness to apply the 105 clamping pressure of the screws 12 evenly about the periphery of the diaphragm. The quality of the note is improved and 110 destructive vibration and cutting action of the diaphragm is prevented by washers 13 and 14 arranged between the diaphragm and the clamping faces of each section of the case. These washers may be of non-vibratory material such as cork, wood, or hardened fiber. The diaphragm 1 is provided with a wear piece 15 formed with a 115 shank 16 riveted over a washer 17. By 120 reference to Figs. 1 and 2 it will be seen that this wear piece is somewhat similar to that set forth in my prior Patent No. 883,643. The wear surface, however, is integral therewith and projects sufficiently so 125 that it may be hardened while the rivet portion is maintained in an annealed condition. This wear piece is formed with its wear surfaces transversely of the direction of rota-

130

tion of the cam and the surfaces are symmetrical in both directions. The section 2 of the diaphragm case is formed with webs 18, 19, having alined openings for support 5 of the cam shaft 20. The latter is mounted in a bearing sleeve 21 with its axis eccentric to but preferably parallel with the axis of said bearing 21, as shown more clearly in Fig. 2. When said bearing is rotated, the 10 axis of the shaft moves in a circular path approximately parallel with the axis of the sleeve. In practice, I find that the radius of this eccentricity need not be much greater than the amplitude of vibration of the diaphragm, in order to give a throw amply sufficient for all required adjustment of the cam shaft with respect to the diaphragm. The sleeve bearing 21 is held in a desired 15 position of longitudinal adjustment by 20 means of the screw collar 22 engaging the end wall of the casing. This collar is locked in position by means of a screw key 23, screw threaded into collar 22 and having a stud 24 engaging a recess in sleeve 21. There 25 is a coöperating lock nut 25 outside of the casing which may be loosened to permit rotary adjustment of the sleeve bearing 21 and the cam shaft 20 carried thereby and which may be tightened to rigidly clamp 30 said bearing against both longitudinal and rotary movement. The cam 26 is keyed to the cam shaft 20 by pin 27 and is clamped against shoulder 28 by locknuts 29.

Oil for lubricating the shaft 20 and also 35 the contact between cam 26 and wear piece 15, is supplied through an oil passage or reservoir 30. Part of the oil is thrown by centrifugal force from the rapidly revolving cam against the projection 15 and part 40 of it finds its way through the opening 31 arranged longitudinally of the shaft 20 and extending down to the bearing point of the latter upon sleeve 21. In order to avoid too great friction, the interior of sleeve 21 is cut 45 away so as to be out of contact with the shaft 20 from the point 32 downward. In the form shown herein, the bearing sleeve 21 is extended outside of the case and is utilized as a support for the motor case 33. As 50 shown more clearly in Fig. 2, this case is concentric with the cam shaft 20, while the bearing sleeve is slightly eccentric thereto, as indicated at 34, though this eccentricity may be so small as to be practically un- 55 noticeable to the eye from the exterior. The end of the sleeve 21 is formed as an end wall 35 of the motor case 33 and is secured to the latter by screws 36, 36. On the cam shaft 20 is mounted the motor armature 37 60 revolving between pole pieces 38, 38, formed as integral projections of the shell or case 33 and energized by field windings 39, 39. The case 33 is closed in at the bottom by an inclosing wall 40 formed with a journal 41 65 for the lower end of shaft 20. Surround-

ing this is an annular cavity 42, supplying lubricating oil or grease through passages 43. The lubricant is held in position by means of a disk 44, engaging the annular shoulder 45. The current for operating the 70 motor is derived from battery 46 controlled by circuit closers, as at 47, and, if desired, regulated by an adjustable resistance R. This circuit is connected to binding posts 48, 48, leading within the case 33 and insulated therefrom by bushings 49, 49. As diagrammatically indicated by dotted lines in Fig. 1, the current is supplied in parallel to the field windings 39, 39 and to the brushes 50, 50 of commutator 51 supplying 80 armature 37. Above the armature 37, upon the armature shaft 20, adjacent the end of sleeve 21, is arranged a collar 52, whereby the drip of excess oil is thrown off centrifugally on the sides of the case 33 and so is 85 prevented from saturating the armature and leaking down on the commutator, thereby impairing the contact of the commutator bars therewith.

By reference particularly to Fig. 2, it will 90 be seen that the adjustment of the cam shaft to and from the diaphragm may be accomplished by rotating the eccentric sleeve 21 through a quarter rotation in either direction from the medial position shown in said 95 Fig. 2 and that rotation through a semi-circumference from said position will bring the axis of the cam shaft to a position where it is exactly the same distance perpendicularly from the diaphragm, but is on the left hand side of the axis of sleeve 21. In certain cases, it is confusing to unskilled users to have an adjustment of this kind wherein a continuous rotation in one direction acts as an adjustment toward the diaphragm 100 through a half revolution, and then as an adjustment away from the diaphragm during the other half revolution. I may avoid this by arranging the seats 60, 61, shown in dotted lines in Fig. 2, adjacent the collar 105 22 so as to be engaged by the head of screw 23, thereby limiting the rotary adjusting movement to a half revolution, in which all rotary movement in one direction carries the cam shaft toward the diaphragm and 110 all rotary movement in the other direction carries the cam shaft away from the diaphragm.

As hereinbefore explained, it is very important to time the cam contacts so that the 115 elastic return movement of the diaphragm may be permitted to extend through normal and to a desired distance beyond normal, so that the kinetic energy of the high velocity return movement will be usefully expended 120 in storing up potential energy in the form of elastic stress. In actual practice, I find that where this timing is accomplished by proper spacing, altitude, and speed of the 125 cam projections with respect to the power 130

of the motor, the rotary cam need not have carefully designed curved faces, but may be formed as true straight line planes, as shown in Figs. 3 and 4. In Fig. 3, the operative faces 70 on the advancing sides of the cam projections are formed as plane surfaces. Each surface 70 is for convenience cut back so as to form an abrupt, approximately radial shoulder 71 in the rear of the next adjacent cam projection so that the contour of the cam somewhat resembles a ratchet wheel with the tips of the ratchet teeth ground off. The tips are ground off not so much for the purpose of making the rotor periphery concentric with the shaft but rather for the purpose of providing flat surfaces for impact of the diaphragm wearpiece at nonsynchronous speeds, the violence of these impacts being such that it is difficult to find materials capable of withstanding them if the tips are left sharp. If hard enough not to be deformed by the blows the material is apt to crumble and if soft enough not to crumble, is apt to deform. In actual manufacture, the plane surfaces 70, are cut in the periphery of the rotary cam by an ordinary milling machine. The material is then tempered. This results in some deformation, which, in practice, is sufficiently corrected by grinding off the tips of the projections, as at 72, so that the periphery is accurately centered with respect to the axis of the cam shaft.

In Fig. 4, the plane milling is carried through so that no shoulders are formed as in Fig. 3, the periphery being a regular polygon. In a compact portable device, such as herein disclosed, the desirable diameter of cam is limited to some extent by the comparative inefficiency and feeble torque of the armature when the current is first turned on, and, in most cases, where a polygon of such limited diameter is used, I prefer an octagon, such as shown, though polygons of from five to twelve sides have been used successfully. In Fig. 3, there are ten cam projections, but the effective cam pitch of each projection corresponds to the pitch of the points of a regular hexagon.

In practice, I prefer to make the diaphragm and the wear piece thereon light in weight, thereby decreasing inertia as far as may be consistently with the requirements of stiffness and durability. The diaphragm is preferably of fine quality rolled steel, such as vanadium nickel steel, and may be used either tempered or annealed, though the tempered diaphragm gives a better note. A resonator associated with the diaphragm tends to govern the frequencies of the diaphragm as well as to amplify and reinforce the movements when they are of the same frequency as one of the resonant frequencies of the resonator, and I prefer to use a resonator having an air column equal to at least

a half wave length of the normal operating frequency of the rotary cam contacts. The air column should have a diameter at the base sufficient to extend over substantially all of the freely vibrating parts of the diaphragm so as to receive large amounts of energy from the diaphragm and also to react upon the diaphragm with strong resonant effect, thereby tending to hold the diaphragm and through it the cam and motor to the resonant frequencies slightly above the natural frequency of free bodily vibration of the diaphragm, throughout wide variations of power. Hence, I make the diameter of the base of the resonator between one-third and two-thirds of the unclamped part of the diaphragm. It is preferably flared toward the open end so as to spread the sound and to modify and enlarge the range of frequencies to which the air column will resonate effectively. The horn is preferably similar in design to that shown in my Design Patent No. 39,801, Feb. 2, 1909. By way of illustration, I may say that I have used successfully a steel diaphragm 5 to 6 inches in diameter, .02 to .03 inch in thickness, clamped $\frac{1}{2}$ inch about the edge, in connection with rotary cams having the proportions shown in the drawings and made of highly tempered steel. A desirable 95 motor for use on ignition batteries of automobiles is a direct current shunt wound motor adapted to drive the rotary cam at about 450 revolutions per second when operating on five to seven volts, and preferably 100 capable of taking 12 to 20 volts for periods of ordinary use without damage to the windings.

Fig. 5 is a diagram showing that in a rotary cam with plane cam surfaces of relatively great peripheral extent, the effective operative pitch in respect to the wearpiece of the diaphragm is accelerated or progressively greater toward the tip. The cause of this is the changing relation of the straight line face with reference to the wearpiece of the diaphragm, as the cam surface rotates past the same. The amount of the acceleration due to this cause, will depend upon the circumferential angle through which the cam face extends rather than upon the physical size of the cam or of cam faces. Hence by selecting a suitable circumferential angular extent for the cam faces, I am able to secure by means of straight face cams, a desired acceleration of the pitch toward the tips for purposes hereinafter referred to. In said Fig. 5 the plane cam face a, b , corresponds to half of one side of a polygon circumscribed about an arc a, c , of a circle having its center at d . The arc a, c represents the effective base of the cam projection, the radial distance c, b being the effective altitude. The rate of increase or acceleration of the operative pitch of the plane surface a, b 130

as it travels past the wearpiece on the diaphragm corresponds to the increasing altitudes along the lines e, f, g, h, i , etc. In this case the arc a, c through which the cam face 5 extends is a very considerable one and hence departs very materially from a straight line so that the effective pitch of the cam, instead of being uniform from a, c as might be imagined from its straight line form is in fact 10 of steadily and very materially increasing pitch toward the tip. In order to show more clearly to the eye, the rapidity of this acceleration of pitch toward the tips, I have shown in the upper part of the diaphragm 15 an equivalent cam with the same base, altitude and rate of change of pitch but the base is a straight line instead of an arc and the movement is a longitudinal movement lengthwise of said straight line instead of 20 a circular movement endwise of the circular line a, c . The linear speed of the base $a' c'$ is supposed to be the same as the peripheral speed of the base a, c so that the operative rate of change of pitch of the respective 25 altitude e', f', g', h', i' , is the same as that of e, f, g, h, i . By considering the cam projection a', b', c' as the equivalent of the rotating projection a, b, c and by assuming the relative movement of cam and diaphragm to 30 consist of a lateral movement of the diaphragm along the cam, instead of vice versa, it is possible to indicate some of the important relations diagrammatically, as, for instance, some of the effects of change of speed, 35 spacing, and adjustment of the cam projections relatively to the diaphragm. For this purpose, I have associated with the cam a', b', c' a straight line k, l along which the wear piece of a diaphragm projection, such as 15, 40 Fig. 1, is supposed to move in the direction of the arrow at a rate equal to a given peripheral speed of the cam projection a, b, c . In order to show several relations in a small diagram, I have considered the diaphragm as already in vibration and at the 45 top of the outward swing away from the cam at the instant it passes the point m . The lateral movement parallel with the line k, l combined with the vibratory movement 50 of the diaphragm, causes the diaphragm projection to describe a wave line curve, somewhat as indicated at m, n, o, p, q, r, s, t .

It will be understood that the form and proportion of this curve will depend upon 55 the proportions, materials, and other peculiarities of the diaphragm and co-operating parts, and, in general, the characteristics are exaggerated, the purpose being merely to show some of the operating factors which are involved in transverse bodily 60 vibration of the diaphragm and also something of their relation to the cam. Some of the principal factors involved are as follows: The transverse movement of the dia-

movement of gradually accelerating velocity under the impulsion of the initial elastic stress acting to overcome inertia of the diaphragm. From n to o , the diaphragm swings below normal by inertia acting 70 against increasing elastic stress which gradually overcomes the inertia at o and starts a reverse movement back toward normal. The outward movement from o to normal at p and beyond normal out to a 75 point such as q , if not interfered with, has the same characteristics as the movement from m to o .

It will be evident from the diagram that the amount of power required will be subject to considerable variation according to the particular point in the cycle of vibration at which the cam intercepts the diaphragm contact. In general, it will be seen that where this occurs so that the initial engagement of the cam takes place after the diaphragm has already commenced its outward movement, the forced movement is added to the elastic movement and all of the power of the cam is utilized in doing useful work on 80 the diaphragm. It will be seen also that this is true for all points of interception lying between o and p . If, however, the point of interception is in advance of o and between it and n , the work done by the cam includes checking the inward movement of the diaphragm as well as supplying the power for forcing the outward movement. In case 85 the point of interception is not much in advance of the innermost position, the inertia 90 to be overcome in checking the diaphragm will be small and the reverse elastic stress available for assisting the outward forcing movement of the cam will be great. For instance, in the case of the cam b^2 intercepting 100 the inward swing of the diaphragm at s , the amount of power wasted is small because the velocity of the diaphragm at that point is small and most of the power of the inward movement has already been stored up in the 105 form of reverse elastic stress. Hence, in practice s is a very good point for the cam to intercept the natural rearward swing of 110 the diaphragm. If, however, the speed of relative movement of the diaphragm and cam be increased or the projections be spaced 115 more closely to each other, so that the cam surface b^2 intercepts the diaphragm at a point much in advance of s , the work to be done increases very rapidly, because of the 120 increasing power required to check the inward movement of the diaphragm and the decreased elasticity available to assist the outward movement. When the interception occurs at the point r , all of the energy of the 125 return movement of the diaphragm acts in direct opposition to the cam. Moreover, the diaphragm being then at normal, there is no reverse elasticity to assist the outward movement. Thus my practical device may 130

be designed and adjusted for a certain critical range of speed where slightly increasing the speed of a given rotary cam increases the work done by the cam, by cutting short the movement of the diaphragm below normal, by increasing the velocity at which the diaphragm contact leaves the summit of the rotary cam projection, and by increasing the number of cam contacts per unit time. For 10 these reasons, motive power sufficient to maintain a speed necessary for a given note with the diaphragm intercepted by the cam at or behind the point *s*, is entirely inadequate to maintain the same note with the diaphragm intercepted at *r*. Conversely, 15 considerable variation in the voltage of the current supplied to the motor causes a relatively small change in the note of the horn. The diagram also makes evident that adjustment of the cam toward the diaphragm may be used to harmonize the diaphragm and cam movements for a given suitable power and speed of motor, and that if the adjustment be extended beyond a certain point, it 20 tends to cut short the power saving part of the inward swing of the diaphragm and that it also tends to force the swing more and more in the region beyond normal where the elastic tension of the diaphragm is greater 25 and the forced movements require more power.

The general principles of spacing, speed, and adjustment as explained above with reference to plane faced cam projections, apply 30 equally to other forms of rotary cams having suitably spaced projections of other contour. Thus explained, the diagram shows first, how great engineering efficiency is attainable by mechanically harmonizing 35 the cam forcing movements to the natural swing of the diaphragm; second, it shows that for practical harmonizing the point *s* is almost as good a point for the cam to intercept the diaphragm as are the extreme 40 rear-most points *o* and *t* and third, it shows how and why I have been able to succeed in actually establishing points corresponding to *s* as the practical upper limit of normal 45 full speed operation of my commercial device, so that all instruments of the same model produce the same characteristic note of substantially the same pitch notwithstanding the wide variations of internal 50 friction and battery strength attendant upon 55 practical commercial use.

In practice, it will be found that with my above described designs of cam, diaphragm, wearpiece and motive power, the instrument may be standardized for the desired normal 60 full speed operation by having the cam tips very slightly overlapping the normal equilibrium position of the diaphragm wearpiece. The precise degree of such slight overlap can best be determined by practical 65 test. The locknut 25 is loosened and the cur-

rent is turned on. With the motor case as a handle, the sleeve 21 is rotated and the cam is thereby adjusted to and from the diaphragm until the proper operation is made evident by the great increase in volume 70 and improvement in quality of the tone. The locknut is then tightened and the device may be continued in use indefinitely, the reactions of the diaphragm, as determined by elasticity, inertia, resonance, and variation of point of interception of its vibration by the cam contacts, acting to govern and limit the operation so as to utilize the full amount of power required to speed up the motor through the frequencies where harmonious operation is impossible and to 80 maintain the uniform or standard high frequency producing the uniform or standard body swing note generated by the greatly amplified body swing of the diaphragm on 85 both sides of normal.

While I have herein fully shown and described, and have pointed out in the appended claims certain novel features of construction, arrangement, and operation 90 which characterize my invention, it will be understood by those skilled in the art that various omissions, substitutions, and changes in the forms, proportions, sizes, and details of the device and of its operation, may be 95 made without departing from the spirit of my invention.

The specific structural details whereby the motor and drive shaft are adjustably connected with the rear casing of the instrument are independent of, though usable with, my present invention, and the specific claims for such details are contained in my co-pending application Serial No. 494,120, filed May 5, 1909, of which this application 10 is a division.

Herein, I claim:

1. A horn or signaling device including a diaphragm, a wearpiece and a rotary cam having a plurality of plane peripheral cam faces, each extending through a considerable circumferential angle so that its effective pitch with reference to the diaphragm wearpiece is materially accelerating toward the tip by reason of its rotary movement through such angle, the position of said rotary cam being predetermined or adjusted so that the rotary path of the cam tips very slightly overlaps the normal rest position of the diaphragm wearpiece, whereby the accelerating-pitch portions of the cam operate substantially in the region of naturally accelerating outward movement of the freely swinging diaphragm, in combination with means for driving said cam only in the proper direction to utilize said plane faces as the operative faces of said cam.

2. A horn or signaling device including a diaphragm, a wear-piece thereon, and a rotary cam having a plurality of plane pe-

ripheral cam faces, each extending through a considerable circumferential angle so that its effective pitch with reference to the diaphragm wearpiece is materially accelerating 5 toward the tip by reason of its rotary movement through such angle, and each having concentric peripheral tips, the position of said rotary cam being predetermined or adjusted so that the rotary path of the cam 10 tips very slightly overlaps the normal rest position of the diaphragm wearpiece, whereby the accelerating-pitch portions of the cam operate substantially in the region of naturally accelerating outward movement of the 15 freely swinging diaphragm.

3. A horn or signaling device including a diaphragm, a wearpiece thereon and a rotary cam having a plurality of plane peripheral cam faces, each extending through 20 a considerable circumferential angle so that its effective pitch with reference to the diaphragm wearpiece is materially accelerating toward the tip by reasons of its rotary movement through such angle, the position 25 of said rotary cam being predetermined or adjusted so that the rotary path of the cam tips very slightly overlaps the normal rest position of the diaphragm wearpiece, whereby the accelerating-pitch portions of the 30 cam operate substantially in the region of naturally accelerating outward movement of the freely swinging diaphragm, in combination with an electric motor designed and energized so as to start said cam and drive 35 it up to a speed but slightly greater than the natural frequency of the swing of the diaphragm, but not to over-balance the reactive energy of the diaphragm swing rear- 40 wardly of its normal rest position at that frequency.

4. An alarm or signal comprising a thin elastic steel diaphragm, clamped about its edges and adapted to produce a continuous note by free bodily swings on both sides of 45 its neutral or normal equilibrium position at approximately its natural fundamental frequency, a rotary cam having a plurality of low-pitch, direct-acting, cam projections adapted to apply a direct outward thrust to 50 the diaphragm, the space between said cams being of sufficient depth to permit free inward swing of the diaphragm rearwardly of its normal equilibrium position, an electric motor having an armature shaft on which 55 said cam is mounted, the overlap of cam projections and diaphragm wear-piece being slight and predetermined in respect to the power of the motor for the purpose and with the result of producing only small

amplitude vibrations of small power at sub- 60 normal speeds, but building up wide amplitude swings on both sides of normal equilibrium at a speed giving cam contacts at frequencies slightly above the natural fundamental frequency of the diaphragm, and 65 means for energizing said motor sufficiently to drive the cam up to said latter speed, but insufficiently to overcome the thus amplified power of the diaphragm swings rearwardly 70 of normal, the latter acting to limit and determine the normal speed of the motor, substantially as described.

5. In a device for producing an alarm or warning signal of the class described, a thin elastic steel diaphragm, provided with an 75 attached wearpiece, said diaphragm being clamped about its edges and having its central portion adapted to swing bodily on both sides of its neutral or rest position at a fairly definite natural rate or fundamental 80 frequency, a rotary cam having a plurality of substantially similar, low-pitch cam projections designed and arranged to apply outward thrusts perpendicularly to the diaphragm, the space between the operative 85 cam surfaces being of sufficient width and depth to permit natural inward swing of the diaphragm rearwardly of its neutral or rest position, said parts being positioned with but slight overlap of the rotary path 90 of the cam tips in reference to the neutral or rest position of the diaphragm, in combination with a serially arranged circuit, circuit closer, battery and rotary electric motor having said cam on the armature shaft 95 thereof, said motor and battery being designed, upon closure of said circuit, to give a predetermined power output sufficient to start said cam and drive it up to a speed where the cam contacts occur at a frequency 100 slightly greater than said natural fundamental frequency of bodily swing of the diaphragm, but not sufficient to overcome the amplified reactive energy of the natural 105 swing of the diaphragm rearwardly of its neutral or rest position due to operating at said frequency, thereby determining said speed and frequency of cam contacts as the normal for full speed operation of said warning signal, for the purpose described. 110

Signed at New York city, in the county of New York, and State of New York, this seventh day of July, A. D. 1910.
